TURNBUCKLE WRENCH

Irvin H. Blanchard, Wichita, Kans., assignor to
 Beech Aircraft Corporation, Wichita, Kans., a
 corporation of Delaware

Application July 20, 1943, Serial No. 495,531

2 Claims. (Cl. 81—13)

The invention herein disclosed relates to wrenches for holding and working on turnbuckles, particularly as used on aircraft cables. These turnbuckles are usually located in more or less inaccessible places, can be reached only through small openings and, in many cases are disposed in an intermediate portion of the cable, instead of being anchored at one end, thus requiring that both ends of the turnbuckle be held while making adjustments of the intermediate connecting portion.

The objects of the invention are to provide a wrench particularly suited to such purposes and which, among other things, will be capable of holding both ends of a turnbuckle, while leaving the intermediate portion clear and free for adjustment; which will be of a size and form to readily enter the inspection openings or small spaces through which such turnbuckles may be available; which can be easily manipulated to take hold of one or both ends of the turnbuckle; which when engaged with both ends will hold itself in place; which can be easily snapped into position or be removed from supported relation on the turnbuckle and which will be self-adjusting; in the sense of accommodating itself to the set position of a turnbuckle and thereafter retaining its hold during adjustments of the turnbuckle.

Other desirable objects will appear in the course of the following specification.

The drawing accompanying and forming part of the specification illustrates present practical embodiments of the invention. The structure however may be further modified and changed in various ways all within the true intent of the invention, as will be apparent from the scope of the invention as hereinafter defined and claimed.

Fig. 1 in the drawing is a side elevation of an embodiment of the wrench as applied to and in use for holding an aircraft cable turnbuckle.

Fig. 2 is an enlarged broken end view on substantially the plane of line 2—2 of Fig. 3, with the stem portion of the turnbuckle screw appearing in section.

Fig. 3 is a broken detail of the wrench end of one wrench lever as viewed from the right in Fig. 2.

Fig. 4 is a side view on a smaller scale of a modified form of the invention.

Basically the invention comprises a pair of opposed levers 5, 5, pivotally connected together at 6, and carrying at their free ends, wrench sockets 7, 7, in opposed relation and adapted to

interlockingly engage endwise over the angled head portions 8, 8, of the turnbuckle screws 9, 9.

To offset the pivotally connected parts of the two levers away from the barrel or sleeve 10, coupling the screws together, said levers are shown as angled at 11, at their pivotally connected ends, to form an arch, spaced entirely clear of the barrel.

A spring 12 is shown connecting the spaced sides of the arched levers and serving to draw these levers together to close the wrench sockets over the heads of the screws.

The wrench sockets are shown as having closed outer end walls 13, engageable with the outer ends of the screw heads 8, to serve as stops limiting the approaching movement of the wrench ends.

Engagement of the wrench sockets over the turnbuckle screws, at the outer sides of the head portions 8, is made possible by providing the wrench sockets with openings in the side and end walls of the same as indicated at 14, in Figs. 2 and 3. These side openings are wider than the diameter of the screw stem or cable portions 15, at the outer ends of the screws, but of less width than the internal diameter 16, of the wrench sockets, so as to leave opposed inwardly extending side wall portions 17, of the wrench sockets, which will grip over opposed side walls 18 of the screw heads, to hold the sockets against lateral displacement from the screws.

The tension of the spring drawing the levers together will hold the wrench sockets thus interlockingly engaged over the ends of the screw heads, enabling the wrench to hold itself in place and to accommodate itself to varying adjustments of the barrel, once it has been snapped into position over the screw heads.

To remove the wrench, it is only necessary to spring it open sufficiently to clear the wrench sockets of the screw heads, that is, to carry the retaining lug portions 17, outward clear of the ends of the head portions 8, after which the openings in the sides of the wrench sockets will permit the wrench to move sidewise clear of the turnbuckle.

The arched formation of the levers provides a convenient grip for handling and manipulating the wrench and the spacing of the side portions of the levers by the angled pivotally connected end portions provides ample clearance between the wrench ends for a pin or other tool that may be inserted through the hole 18, for rotating the barrel. The length of these side portions is such as to allow for the free turning of

an inserted tool fully capable of rotating the barrel and this ample space within the arch of the tool, that is, between the levers and the barrel provides free clearance for manipulating and inserting the locking wire through such opening, after the barrel has been turned to the position of proper adjustment.

In the illustration, the wrench heads at the ends of the levers are shown as laterally offset away from each other by outwardly angled portions 19. These provide a desirable normal spacing of the wrench heads, while reducing the overall width of the handle or leverage portion of the tool to dimensions which will readily enter a small inspection opening, such as illustrated in Fig. 1.

By holding both ends of the turnbuckle, the wrench can be utilized to make sure that both screws are entered an equal distance in the ends of the connecting barrel. The wrench can be easily engaged, one way, by slipping one wrench socket over the cable and sliding it along until it catches over the screw head at that end of the turnbuckle and then while holding the other wrench jaw spread open, engaging the latter over the cable at the other end of the turnbuckle and permitting the spring to then draw in this wrench end into similar interlocked position with the screw head at the latter end of the turnbuckle.

Disengagement may be quickly effected by reversal of these actions.

If desired, cooperating stops, such as indicated at 22, in Fig. 1, may be provided to limit the spreading movement of the wrench sockets. With such stop means, the wrench may be employed for holding the end portions of a turnbuckle, for instance, while the barrel is unscrewed and replaced to engage it evenly with both the screw ends, the wrench in effect thus serving as a temporary connecting member for the opposing ends of the turnbuckle.

Also, if desired, coacting stops such as indicated at 23, may be provided at the inside of the levers to limit the approaching movement of the wrench sockets to some position less than that they would ever normally occupy when holding a turnbuckle of the size for which the wrench is designed.

Fig. 4 illustrates a reversed form of the wrench in which the wrench heads are faced outwardly and the spring 20 is of the compression type, engaged between spring abutments 21, on the levers, at the inside of the arch. The stops 22 limit the extent to which the spring will throw the levers open. This form of the wrench can be easily applied by simply pinching the wrench levers together and then after slipping the wrench heads in over the shanks of the screws, permitting the spring to thrust the wrench heads apart until they engage interlockingly over the ends of the screw heads 8.

Various other changes, such as to adapt the wrench to special types of turnbuckles may be made all within the scope of invention defined by the claims.

What is claimed is:

1. A wrench for a turnbuckle having angular

screw heads at opposite ends of the same, said wrench comprising handle levers spaced apart the approximate length of a turnbuckle and having adjustably connected angled ends spacing said levers in substantially parallel relation, a spring connected between spaced apart portions of said adjustably connected levers and tensioning the same in one direction, open-ended angular wrench sockets on the free ends of said levers, in substantial axial alignment to axially coincide with the longitudinal axis of a turnbuckle and arranged with the open ends of the same faced in opposite directions and in the directions in which the respective levers are spring tensioned, to thereby yieldingly engage endwise over said angular screw heads, stop shoulders at the backs of said wrench sockets for engagement with oppositely facing ends of said screw heads to limit the spring tensioning movement of said adjustably connected levers, said wrench sockets having openings through the sides of the same into the angular portions of said sockets and of less width than the diameter of said sockets for enabling sidewise engagement of the wrench sockets over portions of lesser diameter adjoining said screw heads and retaining lugs in the entrance portions of said openings through the sides of the sockets and in line with said sockets for engagement over the side portions of the screw heads after the sockets have been engaged endwise over the angular ends of said screw heads for removably retaining the wrench in gripping engagement with the opposite screw heads of a turnbuckle.

2. A wrench for a turnbuckle having angular screw heads at opposite ends of the same, said wrench comprising handle levers spaced apart the approximate length of a turnbuckle and having adjustably connected ends, a spring connected between said adjustably connected levers and tensioning the same in one direction, open-ended angular wrench sockets on the free ends of said levers, in substantial axial alignment to axially coincide with the longitudinal axis of a turnbuckle and arranged with the open ends of the same faced in opposite directions and in the directions in which the respective levers are spring tensioned, to thereby yieldingly engage endwise over said angular screw heads, stop shoulders at the backs of said wrench sockets for engagement with oppositely facing ends of said screw heads to limit the spring tensioning movement of said adjustably connected levers, said wrench sockets having openings through the sides of the same into the angular portions of said sockets and of less width than the diameter of said sockets for enabling sidewise engagement of the wrench sockets over portions of lesser diameter adjoining said screw heads and retaining lugs in the entrance portions of said openings through the sides of the sockets and in line with said sockets for engagement over the side portions of the screw heads after the sockets have been engaged endwise over the angular ends of said screw heads for removably retaining the wrench in gripping engagement with the opposite screw heads of a turnbuckle.
